UNITED STATES PATENT OFFICE.

JOHN WILLIAM JOHNSON, OF AUCKLAND, NEW ZEALAND, ASSIGNOR OF ONE-HALF TO
LUKE BERNARD DOUGHERTY, OF HAMILTON, NEW ZEALAND.

AUTOMATIC ALARM.

Application filed August 13, 1925. Serial No. 50,129.

This invention relates to warning devices and more particularly to that class of warning device which is adapted to be set in operation on any person interfering with or attempting to remove any article to which or on which such device is attached or placed.

The object of this invention is to provide an improved device for the aforesaid purpose which can be constructed either as a separate unit or can be built into such articles or containers as cash or deed boxes, jewel cases and the like, the device being automatically set in operation to emit or produce a loud warning sound, immediately the article or articles to be protected are interfered with, moved, lifted or attempted to be carried away in any manner.

According to the invention, the device when constructed as a separate unit, is contained in a casing or the like having a hinged upper side or lid, adapted when the said device is set ready for operation, to be secured in its closed position by means of a suitable lock.

The bottom of the casing is positioned some distance from the lower edges of the sides of the same so as to provide an enclosed space between the said bottom and the article which it is desired to protect and on which the device has been placed or is supported.

A tubular member mounted inside the casing is adapted to provide a guide through which a rod is capable of a certain amount of vertical sliding movement, the lower end of the said rod passing through the bottom of the casing and projecting a short distance into the space between the said bottom and the article on which the latter is resting.

A loose ball or the like is positioned between the lower end of the vertical rod and the article to be protected, said ball supporting or retaining the rod at or near the uppermost limit of its sliding movement in the tubular guide.

The upper end of the vertical sliding rod is bifurcated and is adapted to support a balance arm, one end of which is weighted to render it heavier than the other end. The lighter end of the balance arm is provided with a seating on which a ball is adapted to be supported, the weight of said ball being such that the weights of the two

ends of the said balance arm are equalized and the latter is supported horizontally across the upper end of the vertical rod.

Electric contacts on either end of the balance arm are held out of contact with adjustable contacts inside the casing so long as the said balance arm is retained in its horizontal position and so long as the vertical sliding rod remains at the uppermost limit of its sliding movement.

On the device being moved, tilted or lifted in any manner, either the ball will be dislodged from its seating on the lighter end of the balance arm, whereupon the heavier end of the latter will fall to close the electric contacts and complete an electric circuit, or the ball will be moved from underneath the lower end of the vertical rod, and the latter will drop in its tubular guide causing the balance arm as it also drops to close the electric circuit and set in operation an alarm sounding means which will continue to operate until such time as the electric circuit is disconnected.

The invention will be more particularly described with the aid of the accompanying drawing, wherein:

Figure 1 is a sectional perspective view of the device constructed as a separate unit, showing the same set ready for operation.

Figure 2 is a sectional elevation of the device as shown in Figure 1, but showing the same set in operation owing to the device having been slid or lifted off of the article to be protected, and

Figure 3 is a similar view to Figure 2 showing the alarm set in operation by the ball being dislodged from the lighter end of the balance arm.

A strong casing 1 is provided with a removable lid 2 adapted to be secured in its closed position by means of a convenient lock 2a. The bottom 3 of the casing 1 is positioned some distance above the lower edges of the sides of the same so as to provide a space 4 between the said bottom 3 and the article, surface or the like on which the device is supported or stands.

A ball 5 located in the space 4 is adapted to support the lower end of a vertical rod 6 which projects through the bottom 3 and is slidable vertically in a tubular guide member 7. The effect of placing the ball 5 under the lower end of the rod 6 is to retain the latter at or near its uppermost

limit of sliding movement through the guide 7, as shown in Figures 1 and 3 of the accompanying drawing.

The upper end of the rod 6 is bifurcated 5 and has mounted therein, by means of a suitable knife edge fulcrum pin 8, a balance arm 9 one end of which is weighted as at 10 in order to render it heavier than the other end of the said balance arm.

10 The lighter end of the balance arm 9 is provided with a seating 11 adapted to support a ball 12 the weight of which is just sufficient to counteract the effect of the weighted portion 10 of the other end of the 15 balance arm and so balance or restore the latter to equilibrium.

The balls 5 and 12 having been placed in position as herein described, the device is in the position shown in Figure 1 of the 20 accompanying drawing.

The ends of the balance arm 9 are provided with electric contacts 13 and 15, and electric contacts 14 and 16 in the electric circuit of a suitable battery 15^a and bell or 25 other alarm sounding means 20, are mounted adjustably on vertical supports or guides 17 within the casing 1.

Should the device be lifted off, or slid 30 along the surface of the article to be protected and on which latter the device is supported or stands, the ball 5 is either rolled out from under the rod 6, or else the latter drops in its guide 7 as the box is lifted off the article or surface on which the 35 ball rests.

The effect of this is to cause the ball 12 to be dislodged from its seating 11 by the disturbance of the equilibrium of the balance arm 9 as it falls with the rod 6, and 40 the contacts 13 and 14, 15 and 16 are thereby closed to cause electric current to pass through the balance arm 9, rod 6, and tubular guide member 7, from which latter it is led through a wire or wires to the 45 bell 20 or other warning means located in the casing 1.

In the case of the device being lifted off of or slid from on top of the article to be 50 protected as herein before described, it is not essential for the ball 12 to be dislodged from its seating 11 before the warning bell 20 will operate, as the falling of the balance arm 9, even though the latter retains its equilibrium, is sufficient to bring the contacts 13 and 15 into touch with the contacts 14 and 16.

Where the article to be protected by the device is in itself of a portable nature, it might be possible to carry away both the article 60 and the device supported on the latter without operating the alarm, were the displacement of the ball 5 alone to be relied on to cause the closing of the electric contacts.

In such a case, however, the ball 12 being only retained on its seating 11 by means

of a slight depression in the centre of the latter, is easily dislodged and will only remain in position so long as the casing 1 and balance arm 9 remain absolutely steady.

Should it be attempted to remove the device without moving it from the top of the article to be protected, the slightest movement will cause the ball 12 to fall from its seating, whereupon the weighted end of the balance arm 9 will fall and the contact 15 thereon come into touch with the contact 16 in the electric circuit of the bell 20 to operate the latter.

The alarm 20 can only be put out of operation by unlocking the lid 2 of the casing 1 with the proper key and then disconnecting the electric circuit of the bell 20 or the like.

The contact 15 on the heavier end of the balance arm 9 is preferably of hollow rectangular or ring shape, the contact 16 on the upright 17 being in the form of a pin which normally projects inside the said hollow rectangle or ring but does not touch the latter, thereby providing that should the device be turned on its side or upside down in an attempt to stop the alarm once the latter has commenced ringing, no matter in what direction the balance arm 9 lies, the said contacts will still be enabled to touch one another and the alarm to continue ringing.

The vertical sliding movement of the rod 6 is preferably limited by means of a slot 18 in the side of the tubular guide member 7 and a pin 19 projecting from the side of the rod 6 and entered in the said slot 18. This slot and pin prevent rotation of the balance arm 9 and rod 6 out of their normal positions, and consequently ensures that the contacts on the said balance arm will at all times be directly over the contacts on the uprights 17.

Having now described my said invention, I declare that what I claim and desire to obtain by Letters Patent of the United States of America, is:—

1. A theft-foil circuit closer including a sliding support, a balance arm fulcrumed on said support and forming one pole of the circuit closer, means constituting the other pole, in operative proximity to said balance arm, and a free ball normally positioned beneath said sliding support for holding said arm out of contact with said other pole.

2. A theft-foil circuit closer including a sliding support, a balance arm fulcrumed on said support, means constituting a fixed pole of the circuit closer, a conductive loop carried by said balance arm freely surrounding said fixed pole and itself constituting the other pole, and a free ball normally positioned beneath said sliding support for holding said balance arm at such

elevation as to maintain said poles out of contact.

3. A theft-foil circuit closer including a sliding support, a balance arm fulcrumed on said support forming one pole of the circuit closer, means constituting the other pole in operative proximity to said balance arm and balls on one of which said support freely rests, the other being balanced on 10 said arm, and each being operable to close said circuit, the one by body translatory movement of said balance arm due to sliding movement of said support and the other by pivotal movement of the arm about its 15 fulcrum.

4. A theft-foil circuit closer including a sliding support, a balance arm fulcrumed on said support and forming one pole of the circuit closer; means constituting the other pole, in operative proximity to said 20 balance arm, and a free ball normally positioned on said balance arm for maintaining the equilibrium thereof said ball being displaced by tilting of said circuit closer.

Signed at Auckland, in the Provincial 25 District of Auckland, in the Dominion of New Zealand, this 13th day of July, A. D. 1925.

JOHN WILLIAM JOHNSON.
